Inventor

Attorney,

UNITED STATES PATENT OFFICE.

HARLAN P. WELLMAN, OF ASHLAND, KENTUCKY.

ELECTRIC HEADLIGHT-LAMP.

SPECIFICATION forming part of Letters Patent No. 630,475, dated August 8, 1899.

Application filed May 6, 1899. Serial No. 715,795. (No model.)

To all whom it may concern:

Be it known that I, HARLAN P. WELLMAN, of Ashland, in the county of Boyd and State of Kentucky, have invented certain new and useful Improvements in Electric Headlight-Lamps; and I do hereby declare the following to be a full, clear, and exact description of the invention, such as will enable others skilled in the art to which it appertains to make and use the same.

This invention relates to electric headlight-lamps for electric-railway cars, having reference to such as are operated by and connected to the power-circuit.

The primary object of the invention is to provide a changeable headlight-lamp which may be operated by and connected to the power-circuit of an electric-railway car without the annoyance and encumbrance of connecting wires and plugs, as commonly employed.

A further object is to provide a removable headlight-lamp capable of being removed in such manner that no injury will be caused to the lamp or contact-terminals in the event that the main-line-circuit switch is not first opened. This I accomplish by breaking contact first at the negative terminal and then at the positive terminal.

The invention also comprehends improvements in the construction and arrangement of various details, all as hereinafter fully set forth, and particularly pointed out in the claims.

In the accompanying drawings, Figure 1 is a view, partly in section and with parts broken away, showing a lamp in which my improvements are embodied. Figs. 2 and 3 are longitudinal sectional views of the automatic circuit-closers with the coacting lamp-terminals in side elevation. The form shown in Fig. 3 is a modification of that shown in Fig. 2. Fig. 4 is a rear view of the casing in which the resistance is located, the lid or door being raised and broken away. Fig. 5 is a plan view showing the lamp-casing partly removed from its support. Figs. 6 and 7 are plan and front elevations, respectively, of a slight modification. Fig. 8 is a side view embodying the arrangement contemplated by the construction in Figs. 6 and 7. Fig. 9 is a side elevation

showing the chamber for the circuit-closers vertically disposed and with the lamp-casing resting thereon.

Referring to the drawings, A designates a casing which projects through an opening in and is rigidly secured to the car-dash a, or it may be the front end of a car or vestibule thereof. This casing is provided with a door a', which may be held when closed by a spring-catch a². Within the casing is located a suitable resistance B, composed, preferably, of wires having a high specific resistance to the passage of an electric current. Also within this casing is a fuse and block therefor (indicated at b, Fig. 4) and two terminals consisting of circuit-closers 1 and 2, located within cylindrical portions b', which are open at the forward ends save when covered by a hinged cap b². The circuit-closer 1 is automatic and is of the end-contact-follower style. The circuit-closer 2 is fixed. In Fig. 2 I have shown a stationary terminal 3 and a movable plunger 4, normally held away from the former by a coiled spring 5. These parts are located within a bushing 6 of porcelain or the like. In Fig. 3 the plunger 4' has its stem passed through an opening in the terminal 3'.

C is the lamp-casing, d the reflector therein, and 7 and 8 the negative and positive terminals, respectively, of the lamp-circuit. These terminals may have a spring-held projection 9, as shown in Fig. 2, or this projection may be rigid, as shown in Fig. 3. They are designed to engage the circuit-closers 1 and 2. By using the terminal with the spring-held projection no buffer is required to receive the blow when the lamp is being positioned, the projection 9 serving the same purpose. To the rear wall of the lamp-casing is pivoted a right-angular bracket D, carrying at its outer end a pin d' for entering an apertured ear d², projecting from the casing A. The vertical arm of this bracket is normally held against the wall of the lamp-casing by a spring d³, encompassing a bolt d⁴, carried by said arm and extended through a hole in the lamp-casing. The placing of the bracket D in engagement with casing A allows the projecting terminals 7 and 8 to automatically contact with the movable spring-held plunger of the circuit-closer 1 and the fixed circuit-closer 2,

thereby connecting the lamp-circuit automatically with the working line or trolley power circuit and supplying current to the lamp-carbons. It will be seen that the weight 5 of the lamp holds both the terminals and circuit-closers in contact when the lamp is in its operative position. In removing the lamp current should be broken first at the negative terminal and then at the positive terminal, thereby avoiding any destruction or deterioration at the positive contacts should the lamp be removed without first opening the main headlight line-switch X.

In Fig. 8 is shown an automatic positive 15 end contact-closer e , located in the casing E, bolted or otherwise secured to the car or car-dash. In this arrangement an external resistance 10 is included in the circuit, and the lamp-bracket 12 is shown as being hung on 20 the car-dash. The negative terminal of the lamp makes contact with the lug e' , Figs. 6 and 7, of the casing E, and the latter is grounded. In the front wall of the casing A are formed openings to allow of the escape of 25 heat generated by the resistance-coils.

In Fig. 9 I have shown the chamber F, in which the circuit-closers are located, as being vertically disposed, with the lamp-casing f resting directly thereon. The chamber F is 30 here shown as projecting from and paralleling the casing A; but I do not restrict myself to this combination, as the same arrangement may be observed when casing E is employed.

The operation is as follows: The motorman 35 by positioning the lamp-casing automatically connects the lamp-circuit with the trolley line-circuit. In removing the lamp the motorman tilts it on the pivot of the bracket D so that the bottom will be thrown forward in over- 40 coming the tension of the spring d^3 , and then the lamp may be lifted out of position. In removing the lamp the negative terminal is first disconnected and then the positive terminal, for the reason and with the advantage 45 hereinbefore recited.

Changes may be made in the construction and arrangement of the parts without departing from the scope and spirit of my invention.

50 I claim as my invention—

1. The combination with a casing mounted on a car and having positive and negative circuit-closers, and a resistance intermediate the latter and the trolley-wire circuit, of a lamp and its casing having projecting terminals for contacting with the circuit-closers, one terminal and its coacting circuit-closer having a following contact, the other terminal having a fixed contact with its coacting 55 circuit-closer, as set forth.

2. The combination with a casing mounted on a car and having positive and negative circuit-closers, and a resistance intermediate the latter and the trolley-wire circuit, of a lamp 60 and its casing, terminals projecting from such casing for contacting with the circuit-closers,

and a support for the lamp pivoted to the latter near the top thereof, one terminal and its coacting circuit-closer having a following contact, the other terminal having a fixed contact with its coacting circuit-closer, whereby in removing said lamp the negative terminal may be first disengaged, as set forth. 70

3. The combination with the casing mounted on a car, a resistance located within such casing, and a fixed contact and a follower-contact, of a lamp having projecting terminals designed to engage such contacts, and a bracket by which said lamp is suspended in position, as set forth. 75

4. The combination with the casing mounted on a car, a resistance located within such casing, an automatic yielding contact also mounted in such casing, and a fixed contact, of a lamp-casing having projecting terminals 85 designed to engage said contacts, a supporting-bracket pivoted to said lamp-casing, and a spring for normally holding the bracket in fixed relation to the lamp-casing, as set forth.

5. The combination with the casing mounted on a car, a resistance located within such casing, an automatic yielding contact also mounted in such casing, and a fixed contact, of a lamp-casing having projecting terminals designed to engage such contacts, a supporting-bracket of right-angular form, pivoted to the lamp-casing, a projection, carried by the bracket, extended through an opening in the lamp-casing, and a spring encircling such projection tending to normally hold the bracket 95 in fixed relation to the lamp-casing, as set forth. 100

6. The combination with the casing, of the automatic, spring-actuated contact, and a fixed contact, in the casing, and the lamp having projecting terminals for engaging such contacts, as set forth. 105

7. The combination with the casing, and the resistance, of the automatic, spring-actuated contact and fixed contact mounted in the casing, and the lamp having projecting terminals for engaging such contacts, as set forth. 110

8. The combination with the casing having open-ended chambers, and a resistance, of the terminals mounted in such chambers, one being fixed and the other having a plunger, a spring acting on such plunger, and a lamp having projecting terminals designed to engage the before-mentioned terminals, substantially as set forth. 115

9. The combination with the casing having open-ended chambers, of the fixed contact, and the spring-actuated contact in such chambers, and the lamp-casing having projecting terminals designed to engage said contacts, 125 one of said terminals being spring-pressed, substantially as set forth.

10. The combination with an electric-railway car and the dash having an opening therein, of a casing projected through such opening, resistance material within the casing, a fixed contact and an automatic yielding con- 130

tact within the casing, and a lamp having projecting terminals for engaging such contacts, substantially as set forth.

11. The combination with the casing, of the fixed and automatic follower-contacts, mounted in such casing, and the lamp-casing having yielding and positive terminals for engaging such contacts, as set forth.

In testimony whereof I have signed this specification in the presence of two subscribing witnesses.

HARLAN P. WELLMAN.
